UNITED STATES PATENT OFFICE

151,000

DESIGN FOR A DROP-LEAF EXTENSION
TABLE

Cedric E. Millspaugh, Westlake, Ohio, assignor to Union-National, Inc., Jamestown, N. Y., a corporation of New York

Application March 27, 1947, Serial No. 137,939

Term of patent 14 years

(Cl. D33—14)

To all whom it may concern:

Be it known that I, Cedric E. Millspaugh, a citizen of the United States, residing at Westlake, in the county of Cuyahoga and State of Ohio, have invented a new, original, and ornamental Design for a Drop-Leaf Extension Table, of which the following is a specification, reference being had to the accompanying drawing, forming part thereof; and in which

Fig. 1 is a perspective view of an extension table, showing my new design with the drop-leaves in raised position;

Fig. 2 is a perspective view similar to Fig. 1, showing the table with the drop-leaves in lowered position;

Fig. 3 is a side elevational view of the table with the drop-leaves in lowered position; and

Fig. 4 is an end elevational view with the drop-leaves in raised position.

I claim:

The ornamental design for a drop-leaf extension table, substantially as shown.

CEDRIC E. MILLSPAUGH.
